UNITED STATES PATENT OFFICE.

JOHN BERRY, OF SPRINGFIELD, MASSACHUSETTS, ASSIGNOR TO THE NATIONAL NEEDLE COMPANY, OF SAME PLACE.

MACHINE FOR SWAGING NEEDLE-BLANKS.

SPECIFICATION forming part of Letters Patent No. 257,645, dated May 9, 1882.

Application filed May 11, 1881. (No model.)

To all whom it may concern:

Be it known that I, JOHN BERRY, of Springfield, in the county of Hampden and State of Massachusetts, have invented a new and useful Improvement in Machinery for Compressing Needles, of which the following is a specification and description.

The object of my invention is to provide a machine for forming needles in which one of the forming-dies may be adjusted with reference to the other, and in which both may be adjusted to the axis of the clamp which holds the needle while being formed, and in which the said clamp is provided with a beveled fastening-key to secure the needle in the clamp and prevent it from becoming loose therein while being formed, all which will be more fully hereinafter described, and illustrated in the accompanying drawings, in which—

Figure I is a front view of a needle-forming machine having my invention applied. Fig. II is a side view of the same. Fig. III is a longitudinal vertical section of the needle-holding revolving clamp having my fastening-key applied thereto. Fig. IV is an end view of the clamp and the clamp-carriage. Fig. V is a vertical transverse section of the lower die and its plunger, showing the device for adjusting the die to give it the desired movement. Fig. VI is an end view of the adjusting-disk and its eccentric. Fig. VII is an end view of the beveled slot in the clamp-spindle and fastening-key which operates therein. Fig. VIII is a vertical section through the machine, showing the dies and the guideway upon which the carriage moves which carries the clamp for holding the needle-blank while being formed; and Fig. IX is a front view of the die-holders or plungers and dies secured therein.

In the drawings, A represents the frame of the machine, provided with suitable guide ways or plates, between which are secured a block, as *a*, and also a plunger, as *b*, the latter, so as to move in a vertical direction, being actuated by two knuckle-bars, 2 and 2', the former pivoted at its upper end to said plunger and at its lower end to a pitman, as 3, connected with a crank-shaft, and the bar 2' pivoted at its upper end to said pitman and at its lower end to a block held between suitable ver-

tical guide ways or plates at the lower part of the frame. The upper forming-die, 3, is firmly fixed in the block *a*, and the lower forming-die, 4, is nicely but loosely fitted in the upper part of the plunger *b*, its movement downward being limited by a device which I shall now proceed to describe, while the movement of the plunger continues to the full extent required by the throw of the toggles. This device (shown in Figs. V and VI) consists of a disk, F, having a semicircular slot, 14, through it. From one side of this disk projects a cylindrical plug, as 13, concentric with the slot 14, and from the end of this plug projects a short pin, as 5, eccentric to the plug 13 and slot 14. A cavity is made in the back side of the plunger *b*, just beneath the die 4, and a hole is made through the plate E', and the plug 13 is inserted through the hole in the plate, with the pin 5 projecting into the cavity in the plunger beneath the die, and this plug and its projecting pin may be turned in either direction and secured by a screw, 7, inserted into the circular slot in the disk and turned into a threaded hole in the plate E'. 75

Suppose the pin 5 to be in its lowest position, as shown in Fig. VI, if the disk F be turned in either direction, of course the eccentric-pin 5 will turn also, and will rise in revolving around the axis of the plug 13. As the die 4 is lifted always to the same point of elevation, and as the die drops down upon this eccentric-pin 5, it is evident that this pin controls the downward movement of the die 4, and that this movement is limited in extent according to the position of the pin 5, while the plunger *b*, being pivoted to the upper end of the knuckle-bar 2, will have the same up-and-down movement as said bar 2. 80

The piece *a*, as well as the piece 11, is always held stationary by the plates between which it is clasped, and the piece *a* is recessed to receive the die 3, which is permanently fixed therein, and half the form of the needle is made in the lower end of the die 3, and the other half is made in the upper end of the die 4, and both together give the desired form to the needle when the blank is held between. 85

Upon one side of the frame is made a guideway or slide, B, upon which is fitted to move 90

freely a carriage, as 12, at right angles to the dies 3 and 4, and a spindle, as 14', is arranged to revolve in a bearing in this carriage, with a handle, as 17, pivoted at one end to a stud, as 15, on the carriage, with a yoke, as 19, inclosing a sleeve, as 20, hung on two screw-studs or trunnions turned through opposite sides of the yoke. The spindle extends through this sleeve 20 and is made hollow for a portion of its length. A tube, as 25, is fitted to the bore of the spindle, to slide therein, and into the end of said tube is snugly fitted a clamp, as 29, whose jaws at the ends are made to spring open by their own elasticity, and the exterior of the clamp at the 15 end is made conical, as shown in section in Fig. III. A plug, as 28, may be screwed into the tubular end of the clamp, the end of which plug, when at the proper distance from the jaws of the clamp, serves as a gage against which 20 the end of the needle-blank is placed when fixed in the clamp to be formed, thus insuring uniformity in the needle-blanks.

A piece, 27, having an interior conical shoulder, 30, to fit against the exterior conical end 25 of the clamp, is screwed to the threaded end of the spindle 14', and a slot, as 21, which in Fig. III is shown in a vertical position, and whose form in plan view is shown in Fig. VII, is made in the spindle 14', one end of which 30 slot is inclined and the other end vertical; and an inclined slot, 22, is made in the sleeve 20, with its upper and lower ends inclined to a horizontal plane, but both ends parallel, as shown clearly in Fig. III; and a piece, as 23, is fitted 35 lengthwise into the slot 22, so as to slide easily, but whose width corresponds in form to the ends of the slot 21 in the spindle. This piece 23, which I denominate a "key," is made beveled or wedge-shaped on its rear edge, and a vertical slot, 21, 40 is correspondingly beveled or wedge-shaped, with a small space between the extreme rear edge of the key and the extreme rear edge of the slot, so that the key may wedge snugly into the slot without the extreme rear edge of 45 the key coming into contact with or impinging against the extreme rear beveled end of the slot. When the key 23 is forced down by its contact with the upper inclined end of the slot in the sleeve in the movement of the latter, the key is made to nearly fill the slot in 50 the spindle, the rear beveled edge of the key being wedged into the beveled portion of the slot in the spindle, and the key is thereby firmly held in place; but when the key is 55 driven upward by contact of the lower inclined end of the slot in the sleeve with the lower end of the key the latter becomes loose in the slot in the spindle. If the extreme rear edge of the key 23 should impinge against the extreme rear end of the slot in the spindle, between the beveled sides, by reason of any undue wear, such extreme edge of the key may 60 be filed off and permit the portion of the key to fit snugly and closely the beveled parts of 65 the slot. A rod, as 24, threaded at its end, is turned into the threaded end of the tube 25.

As thus arranged, it will be seen that, if the handle to this yoke and sleeve be moved on the spindle 14' a very short distance in a direction away from the clamp, the key 23 will 70 be forced upward by the lower inclined end of the slot 22 in the sleeve, and the rod 24, tube 25, and clamp 29 are free to be moved back, and the jaws of the clamp will spring open and release whatever is held therein; but if 75 the handle, yoke, and screw be moved a little toward the clamp the key 23 will impinge against the end of the rod 24 and force it and the clamp inward, the conical end of the jaws being forced against the interior conical shoulder, 30, of the piece 27, and the jaws will be thus forced together to grasp a needle-blank, if placed therein. One of the advantages of this construction of a clamp having a wedge-shaped or beveled key is that the constant jar 80 of the machine in operation will not cause the jaws to lose their hold of the needle-blank.

Of course it is essential that the matrix in the lower end of the upper die, 3, and that in the upper end of the lower die, 4, both which 90 give form to the needle, should be exactly coincident with the axis of the clamp which holds the blank while being formed, and for the purpose of effecting such an adjustment of the dies 3 and 4 I provide the adjusting-screws G 95 and H. By turning the crank and its pitman so that the knuckle-bars 2 and 2' are exactly in the same vertical line, as shown clearly in Fig. VIII, and loosening the plates so that the permanent pieces a and 11 may be moved, the 100 adjusting-screw G is turned up or down until the center of the matrix in the upper end of the die 4 coincides with the axis of the clamp, when the plates are again tightened against the piece 11 and the set-screw I is turned in against 105 the adjusting-screw G to hold it firmly. The adjusting-screw H is then turned to adjust the piece a and its die 3 down to the die 4, and the plates E and D are then tightened against the piece a by its screws and the set-screw I 110 turned in against the adjusting-screw H. Power being applied to the shaft 9, the die 4 is forced up against the needle-blank placed between the dies, making two compressions of 115 the needle-blank in one revolution of the shaft.

In forming a needle-blank the handle 17 is drawn back a little, which allows the jaws of the clamp to open. A blank is placed in the jaws and the handle moved in quickly, and the blank is firmly held in the clamp. The carriage is then moved up, moving the blank in between the dies, and the blank is rapidly compressed into the desired form by the operation of the dies and knuckle-bars, and the carriage is then drawn back, its handle moved back a 120 little, the blank withdrawn, and another inserted.

It will be seen that the needle-blank is given the approximate form of a needle by a rapid succession of compressions between the dies 125 3 and 4, instead of being hammered into form by distinct blows or concussions, and this pro-

cess of compression imparts a firm character and fine texture to the metal of the needle while the latter is revolved by the chuck.

This machine does its work effectually and uniformly, and its parts may be comparatively light and move with great rapidity, and the more so from the fact that with this adjustment of the lower die, 4, in its plunger *b*, the dies require to be separated only just enough to release the needle-blank from each compression and allow it to be revolved between the dies to receive the next compression, the blank being thus compressed uniformly and rapidly at every point in its whole structure.

I wish it to be understood that I do not claim the operation of two dies by means of knuckle-jointed bars connected with a pitman and crank; neither do I claim a clamp for clamping or holding a needle; but

Having described my invention, what I do claim as new is—

1. In a machine for forming needles, the combination of two forming-dies, one stationary and the other made movable and loose in a reciprocating plunger, and an adjustable stop for arresting the downward movement of said loosely-fitted die, two knuckle-jointed bars connected with a pitman and crank for actuating said plunger, and two adjusting-screws for adjusting said forming-dies in either direction in the line of movement of said plunger, substantially as described.

2. In a machine for forming needles, the combination of two forming-dies, one stationary and the other made movable and loose in a reciprocating plunger, two knuckle-jointed bars connected with a pitman and crank for actuating said plunger and die, two adjusting-screws for adjusting said forming-dies in either direction in the line of movement of said plunger, and a revolving clamp for holding the needle-blanks while being formed, substantially as described.

3. In a machine for forming needles, the combination of two forming-dies, one stationary and the other made movable and loose in a reciprocating plunger, two knuckle-jointed bars connected with a pitman and crank for actuating

ing said plunger and die, an adjustable arm extending into a cavity in the plug beneath the movable die and secured in any desired position in the guideway of the plunger, for limiting the movement of the movable die, and two adjusting-screws for adjusting the forming-dies in either direction in the line of movement of the plunger, substantially as described.

4. In a machine for forming needles, a revolving clamp for holding the needles while being formed, consisting of a tubular spindle provided with a slot having its rear edge beveled on both sides, and containing a key correspondingly beveled on its rear edge for preventing said key from being accidentally jarred loose, an annular grooved sleeve having a movement along said spindle, and provided with a slot having inclined parallel ends to actuate said key, sliding jaws moving within said spindle and operated by the said key, in combination with dies for forming the needles, substantially as described.

5. In a machine for forming needles, the combination of a fixed die, a reciprocating plunger, a movable forming-die actuated by said plunger, fixed guide-plates for guiding said plunger, a revolvable plug inserted into one of said plates, provided at the end with an eccentric-pin projecting into a cavity in the plunger beneath said movable forming-die, and adapted at its outer end to be adjusted and secured in any desired position, whereby the throw or length of movement of the movable die in the plunger is regulated or controlled, substantially as described.

6. In a machine for compressing needles, the combination of two forming-dies, one stationary and the other movable between two guide-plates, two knuckle-jointed bars to actuate said movable dies, and connected with a pitman and crank, and a revolving clamp for holding the needles while being compressed, substantially as set forth.

JOHN BERRY.
